UNITED STATES PATENT OFFICE.

CHARLES J. ERICKSON, OF CHICAGO, ILLINOIS, ASSIGNOR, BY MESNE ASSIGNMENTS,
TO FIRST TRUST AND SAVINGS BANK, TRUSTEE, OF CHICAGO, ILLINOIS.

POLE-CHANGER.

1,181,656.

Specification of Letters Patent.

Patented May 2, 1916.

Application filed April 22, 1907. Serial No. 369,417.

To all whom it may concern:

Be it known that I, CHARLES J. ERICKSON, a citizen of the United States of America, and resident of Chicago, Cook county, 5 Illinois, have invented a certain new and useful Improvement in Pole-Changers, of which the following is a specification.

My invention relates to pole changers for use in various connections, such, for example, as party telephone lines, and for other 10 purposes requiring alternating currents.

Generally stated the object of my invention is to provide an improved and highly efficient pole changer for converting a direct current or battery current into an alternating current.

Special objects of my invention are to provide an improved arrangement by which the pendulum of the pole changer may directly 20 control both the primary circuit of the transformer and the circuit of the operating magnets; to provide an improved construction whereby the full voltage of the battery is employed for energizing the operating 25 magnets, and only half or a portion of the battery for energizing the primary coil of the transformer; to provide an improved arrangement whereby the pendulum is adapted to shift the middle terminal of the battery 30 alternately into connection with one or the other of the two ends of the battery, and to interrupt a separate or independent circuit including the entire battery; and to provide certain details and features of improvement and combinations tending to increase 35 the general efficiency and serviceability of a pole changer of this particular character.

To the foregoing and other useful ends, 40 my invention consists in matters hereinafter set forth and claimed.

In the accompanying drawings, Figure 1 is a top view of a pole changer embodying the principles of my invention. Fig. 45 2 is a front elevation of the same. Fig. 3 is a sectional view on the line 3-3 in Fig. 1 except that the screw j' is not shown in section. Fig. 4 is a diagram of the circuits of my improved pole changer. Fig. 5 is a partial sectional view on line 5-5 in Fig. 2. As thus illustrated, my invention 50 comprises a base or body A having uprights or standards a connected by a horizontal bar a' . The upright electromagnets B are mounted on the bar a' and connected by a

yoke b of non-magnetic material. The armature C is adjustably secured to the shorter end of the pendulum-rod D, which latter is rigidly secured to a torsion spring E, as shown more clearly in Fig. 5. The latter is a thin flat spring and is secured to the yoke b by the screws e which pass through slots or holes in the ends of said spring. The pendulum rod D is provided near its upper end with an enlarged shoulder d' . The portion d^2 of the pendulum rod above the shoulder d' is threaded. The pendulum rod is firmly secured to the spring E by passing the portion d^2 through a hole in the center of the spring and clamping said spring between the shoulder d' and a nut 65 12. The armature C is secured to the upper portion of the pendulum rod by being clamped between the thumb nut 14 and the hexagonal nut 15, the threaded stem d^2 70 passing through a hole in said armature. The pendulum weight d is secured to the lower end of the pendulum-rod, and when the pendulum vibrates it does so against the torsion of the spring E, which latter can be 75 tuned for any desired rate of vibration. The said armature is polarized by a permanent magnet F which has its lower end mounted upon the bar a' , and which has its upper end provided with a bracket or cross-piece G upon which are mounted the adjustable contacts or terminals g and g' , which latter are suitably insulated. The contact springs H and I are mounted upon the armature C, and are out of engagement with 80 the contacts g and g' , when the pendulum is at rest. The said pendulum also carries an insulated enlargement d^4 adapted to operate the spring contact J, which latter is secured to and insulated from the bracket 85 j . An adjustable contact j' is also mounted in the horizontal projection j^2 of the bracket j ; and adapted to engage the spring J, as shown more clearly in Fig. 3. When the pendulum vibrates the contacts J and j' 90 are alternately opened and closed, as will hereinafter more fully appear.

Referring to Fig. 4 it will be seen that the contacts g and g' constitute the terminals of the pole changer, and that the opposite poles of the battery K are connected with these terminals through the medium of a suitable switch L, which is shown open. When the said switch is closed it will be seen that a circuit is immediately completed 105 110

including said entire battery in series with the coils 1 and 2 of the electromagnets, and including the contacts J and J', which are operated by the pendulum. The armature being polarized in the proper manner, such energizing of the electromagnets immediately causes the pendulum to open the contacts J and J'; and to close the contacts g and H, as shown more clearly in the diagram. The opening of the circuit through the magnets tends to deenergize them, and the closing together of the contacts g and H closes a circuit from the negative pole of the battery through the contacts g and H, through the armature, through the conductor 3, and the primary 4 of the transformer, and through the conductor 5 to the middle point of the said battery. This produces a flow of current through the said primary in one direction. The armature is retracted by the torsion spring E which is in the circuit, and to an extent to open the contacts g and H, and sufficiently to close the contacts g' and I, at the same time closing the contacts J and J'. The circuit is thus reestablished through the electromagnet, and at the same time a circuit is closed from the positive pole of the battery through the contacts g' and I, through the armature, through the conductor 3 and the primary 4, and through the conductor 5 to the middle point of the battery. This time, however, the current-flow is in the opposite direction, because it is now from the terminal 6 through the primary to the terminal 7, whereas the first time the flow was from the terminal 7 through the primary to the terminal 6, by reason of the opposite polarity. In this way the current is alternately reversed in the primary 4, with the result that an alternating current is produced in the secondary 8 of the said transformer or induction-coil. I find that a condenser 9 bridged between the terminals 6 and 7 is adapted to increase the efficiency of the arrangement. In this way the pendulum opens and closes its own circuit, which circuit includes the full voltage of the battery. Also, the said pendulum alternately opens and closes the two circuits of the primary 4, which circuits each include only half of the battery, and the polarity being reversed each time that one is substituted for the other. With such arrangement the construction is simple and efficient, and the generating of an alternating current through the medium of a direct current in a pole changer is effectively and easily accomplished. These alternating currents can be used for selective signaling, in party line telephone systems. Each pole changer can be tuned for a different rate of vibration, so that different frequencies can be employed for ringing the different bells on a party line, in any of the well-known ways. Thus it will be seen that two generating

circuits are provided for the primary of the transformer, and that these circuits are alternately opened and closed, one being substituted for the other to reverse the flow of current in the primary. It will also be seen that these alternating generating circuits by which the alternating current is generated in the secondary of the transformer are energized by only half the battery, and that the polarity is reversed each time that one generating circuit is substituted for the other. In this way the full voltage of the battery is employed for energizing the operating circuit through the electromagnets, and only one half of the voltage of the battery for energizing the generating circuits through the primary of the transformer. I find that in practice this arrangement is exceedingly efficient and satisfactory.

85

What I claim as my invention is:—

1. A pole changer comprising an operating circuit, a battery included in said circuit, a pendulum controlling said circuit, an induction coil, and means operated by said pendulum for including a portion of said battery in circuit with said coil, and for subsequently including another portion in circuit with said coil.

90

2. The combination of a battery, a pendulum, a circuit controlled by the pendulum and including the entire battery, a middle terminal for the battery, means operated by the pendulum for shifting said middle terminal alternately from one end terminal of the battery to the other, the pendulum having a support included in circuit, and a polarized magnet for operating said pendulum.

100

3. The combination of a polarized electromagnet, a spring-mounted pendulum, a battery, a circuit including the battery in series with the magnet, a pendulum controlling said circuit, a coil, spring contacts on said pendulum, stationary contacts connected respectively with the negative and positive poles of said battery, adapted to be engaged by said spring contacts on the pendulum, a connection between said pendulum and one terminal of said coil, and a connection between the other terminal of said coil and the middle point of said battery, the pendulum having a support included in circuit.

105

4. A pole changer comprising a magnet, a pendulum operated thereby, a polarized armature rigid with said pendulum, a battery, a circuit controlled by the pendulum and including the entire battery and the winding or windings of the magnet in series, a coil, a plurality of circuits for said coil, and means operated by said pendulum for opening and closing said circuits and reversing the flow of current in said coil, the pendulum having a support included in circuit.

110

5. A pole changer comprising an operat-

ing circuit, a coil, a plurality of circuits for said coil, a pendulum provided with means for controlling all of said circuits, a polarized armature rigid with said pendulum, 5 and a support for said pendulum, said support included in one of said circuits.

6. A pole changer comprising an operating circuit, a battery included in said circuit, a pendulum controlling said circuit, a polarized armature rigid with said pendulum, an induction coil having two separate circuits, and means operated by said pendulum for including a portion of said battery in one of said circuits, and another 15 portion in the other circuit, the pendulum having a support included in circuit.

7. The combination of a battery, an electromagnetically-operated pendulum, a polarized armature rigid with said pendulum, 20 a circuit controlled by the pendulum and including the entire battery, a middle terminal for the battery, and means operated by the pendulum for shifting said middle terminal alternately from one end terminal 25 of the battery to the other, the pendulum having a support included in circuit.

8. The combination of an electromagnet, a spring-mounted pendulum, a polarized armature rigid with said pendulum, a battery,

a circuit including the battery in series with 30 the magnet, a pendulum controlling said circuit, a coil, a plurality of circuits for said coil, spring contacts on said pendulum, stationary contacts connected respectively with the negative and positive poles of said battery, 35 adapted to be engaged by said spring contacts on the pendulum, a connection between said pendulum and one terminal of said coil, and a connection between the other terminal of said coil and the middle point 40 of said battery, the pendulum having a support included in circuit.

9. A pole changer comprising an operating circuit, a battery included in said circuit, a pendulum controlling said circuit, an 45 induction coil, and means operated by said pendulum for including a portion of said battery in circuit with said coil, and for subsequently including another portion of said 50 battery in circuit with said coil, and a polarized magnet for operating said pendulum.

Signed by me at Chicago, Cook county, Illinois, this 17th day of April, 1907.

CHARLES J. ERICKSON.
